[57] CLAIM

The ornamental design for a container lid, as shown and
described.

DESCRIPTION

FIG. 1 is a top perspective view of a container lid,
showing my new design;

FIG. 2 is a side elevational view thereof;

FIG. 3 is a top plan view thereof;

FIG. 4 is a bottom plan view thereof;

FIG. 5 is a top perspective view of a second embodiment
of that shown in FIG. 1;

FIG. 6 is a top plan view thereof; and

FIG. 7 is a bottom plan view thereof.

Fig. 1.

Fig. 2.

Fig. 3.
